UNITED STATES PATENT OFFICE.

ARNOLD STUCKI, OF ALLEGHENY, PENNSYLVANIA.

CAST TRUCK-BOLSTER.

No. 836,474.

Specification of Letters Patent.

Patented Nov. 20, 1906.

Application filed April 16, 1906. Serial No. 312,007.

To all whom it may concern:

Be it known that I, ARNOLD STUCKI, a resident of Allegheny, in the county of Allegheny and State of Pennsylvania, have invented a new and useful Improvement in Cast Truck-Bolsters; and I do hereby declare the following to be a full, clear, and exact description thereof.

This invention relates to bolsters for rail-way-cars, and especially to cast-steel truck-bolsters of T or other shape in cross-section.

The object of the invention is to provide a strong bolster using a minimum amount of material, and especially to increase the lateral stiffness or strength of such bolsters.

In the accompanying drawings, Figure 1 is a plan view of a bolster constructed according to my invention. Fig. 2 is a side view thereof. Fig. 3 is a cross-section on the line 20 3 3, Fig. 1. Fig. 4 is a similar section on the line 4 4, Fig. 1; and Fig. 5 is an end view of the bolster.

The bolster comprises a bottom chord member 1, a top chord member 2, and a vertical connecting member or web 3. At its central portion it is also provided with the transverse web or strut member 4 and with a center plate 5. The end of the bolster is box-shaped, having side members or cheeks 6, which tie together the top and bottom chord members and also provide wearing-surfaces for the truck-columns. These side cheeks are shown provided with a single column-guide 7, although, if desired, a pair of such guides might be used. The bottom member at the end provides spring-seats at 8, and the ends of said bottom member are rounded off, as at 9, to the contour of the springs, thus removing all superfluous metal and reducing the weight of the bolster to a minimum. The end portion is strengthened transversely by the cross-web 10, which braces the column-guides and also keeps the end of the bolster square. The main web member 3 extends 45 out to the end of the bolster, as shown at 11, so as to stiffen the spring-seats. The cross-webs 10 are provided with holes, as at 12, and the main web member 3 is also provided with holes 13, all in order to facilitate the placing of the cores in manufacture and also lightening the bolster without affecting the strength. Side bearing members 15 are provided, those shown being formed with a cavity, although they might, if desired, be made solid on the top and cored underneath in any suitable way. These side bearing members, as well as the center plate 5, can, if desired, be formed separate from the body of the bolster.

The main portion of the bolster is substantially T shape in cross-section, as is common 60 with this class of bolsters.

All bolsters should be strong both vertically and horizontally. As the load in each case is applied at the center, the greatest efficiency is obtained by making said bolsters 65 strongest at the center both against vertical and horizontal loads. To take care of the vertical load, this end is usually obtained by making a bolster of increased depth at its center, as shown; but to economically increase the strength of the bolster horizontally or laterally other means have to be resorted to, since the width of the bolster is limited by the truck construction, the brake-beams, and other accessories which require 70 that the bolster be of practically uniform width from end to end. The top chord member 2 might of course be made thicker; but as the metal would be largely close to the neutral axis of the girder when considered horizontally it would not do much good and would not be economical, as a large additional weight would have to be added in order to produce any effect. All such T-shaped bolsters are provided at the outer 75 edges of their top chord member with flanges or ribs 16. As these are located a maximum distance from the neutral axis of the girder when considered horizontally, a slight addition of metal to said flanges or ribs will very 80 greatly increase the lateral stiffness of the bolster. Accordingly I form these flanges or ribs of increased thickness at the central portion of the bolster, preferably both horizontally and vertically, tapering the same toward 85 the ends, as clearly shown in the several views of the drawings. Consequently the bolster possesses the maximum strength against horizontal stresses at its central portion. If desired, these ribs might be increased in 90 depth only or in width only at their central portions. While they are shown as at the extreme outer edge of the top member of the bolster, this is not necessary, as they might be somewhat in from the edge; but it is preferable 95 to locate them as far from the neutral axis of the bolster as possible. In a similar way strengthening ribs or flanges might be formed on the edges of the bottom chord member of the bolster, as shown at 18, Fig. 3. 100

105 110

What I claim is—

1. A cast bolster for railway-cars of T shape in cross-section having the ribs at the edges of the top member decreasing in width from the center of the bolster toward the ends.
2. A cast bolster for railway-cars of T shape in cross-section, having the ribs at the edges of the top member decreasing in both width and depth from the center of the bolster toward the ends.
3. A cast bolster for railway-cars of T

shape in cross-section, having the ribs at the edges of the top member decreasing in width from the center of the bolster toward the ends and substantially straight to the ends of the bolster.

In testimony whereof I, the said ARNOLD STUCKI, have hereunto set my hand.

ARNOLD STUCKI.
